(57) **CLAIM**

The ornamental design for a packaged terminal air conditioner front panel, as shown and described.

DESCRIPTION

FIG. 1 is a top perspective view of a first embodiment of a packaged terminal air conditioner front panel;

FIG. 2 is a bottom perspective view of the packaged terminal air conditioner front panel of FIG. 1;

FIG. 3 is a front view of the packaged terminal air conditioner front panel of FIG. 1;

FIG. 4 is a first side view of the packaged terminal air conditioner front panel of FIG. 1;

FIG. 5 is a second side view of the packaged terminal air conditioner front panel of FIG. 1;

FIG. 6 is a top view of the packaged terminal air conditioner front panel of FIG. 1;

FIG. 7 is a bottom view of the packaged terminal air conditioner front panel of FIG. 1;

FIG. 8 is a top perspective view of a second embodiment of a packaged terminal air conditioner front panel;

FIG. 9 is a bottom perspective view of the packaged terminal air conditioner front panel of FIG. 8;

FIG. 10 is a front view of the packaged terminal air conditioner front panel of FIG. 8;

FIG. 11 is a first side view of the packaged terminal air conditioner front panel of FIG. 8;

FIG. 12 is a second side view of the packaged terminal air conditioner front panel of FIG. 8;

FIG. 13 is a top view of the packaged terminal air conditioner front panel of FIG. 8;

FIG. 14 is a bottom view of the packaged terminal air conditioner front panel of FIG. 8;

FIG. 15 is a top perspective view of a third embodiment of a packaged terminal air conditioner front panel;

FIG. 16 is a bottom perspective view of the packaged terminal air conditioner front panel of FIG. 15;

FIG. 17 is a front view of the packaged terminal air conditioner front panel of FIG. 15;

FIG. 18 is a first side view of the packaged terminal air conditioner front panel of FIG. 15;

FIG. 19 is a second side view of the packaged terminal air conditioner front panel of FIG. 15;

FIG. 20 is a top view of the packaged terminal air conditioner front panel of FIG. 15; and,

FIG. 21 is a bottom view of the packaged terminal air conditioner front panel of FIG. 15.

(Continued)

The broken lines in the drawings illustrate portions of the packaged terminal air conditioner front panel which forms no part of the claimed design.
